UNITED STATES PATENT OFFICE.

GEORGE WISE, OF SPRINGFIELD, OHIO, ASSIGNOR TO THE ELWOOD MYERS COMPANY,
OF SPRINGFIELD, OHIO, A CORPORATION OF OHIO.

DESIGN FOR LEATHER, PAPER, OR THE LIKE.

5,396.

Specification for Design.

Patented Oct. 5, 1920.

Application filed June 14, 1920. Serial No. 389,037. Term of patent 14 years.

To all whom it may concern:

Be it known that I, GEORGE WISE, a citizen of the United States, residing at Springfield, in the county of Clark and State of Ohio, have invented a new, original, and ornamental Design for Leather, Paper, and the like, of which the following is a specification, reference being had to the accompanying drawings, forming part thereof.

The figure is a plan view of a piece of leather, paper or the like, showing my new design.

I claim:—

The ornamental design for leather, paper, or the like.

GEORGE WISE.
